UNITED STATES PATENT OFFICE.

JASON McGREGOR CHANDLER, OF GROESBECK, TEXAS.

FLUID-VENDING MACHINE.

1,260,871.

Specification of Letters Patent. Patented Mar. 26, 1918.

Application filed February 27, 1917. Serial No. 151,229.

To all whom it may concern:

Be it known that I, JASON McGREGOR CHANDLER, a citizen of the United States, and a resident of Groesbeck, in the county 5 of Limestone and State of Texas, have invented a new and Improved Fluid-Vending Machine, of which the following is a full, clear, and exact description.

My invention has for its object to provide 10 an automatic fluid vending machine having means for shutting off the supply of fluid when fluid to the value of a coin introduced into the machine has been dispensed. The said means is adjustable, and includes a 15 slotted arm in which a roller is disposed, the roller being mounted on a rack which is operatively connected with the remainder of the said means. The angularity of the slotted arm relatively to the pump plunger 20 to which the slotted arm is secured may be regulated with reference to the price of the fluid, so that the fluid will be shut off when fluid to the value of the coin introduced is dispensed, whether the price of fluid is ten, 25 twenty, or thirty cents a gallon.

Another object of the invention is to provide means which are operatively connected by a coin for turning on the fluid; for setting a trigger connected with the means for 30 shutting off the fluid, and for connecting means by which the pump plunger is adapted to operate the indicator. The means which is operatively connected by a coin also serves to close a clutch which completes 35 the connection between the rack and the mechanism operated thereby.

Additional objects of the invention are to provide a second indicator which may be disposed at a distance from the machine, 40 and which will operate step-by-step with the movement of the indicator on the machine; to provide means for closing the coin chutes when all the fluid has been sold, and to provide the chutes with means to reject 45 iron slugs.

Other objects of the invention will appear in the following specification, in which the preferred form of the invention is disclosed.

50 In the drawings similar reference characters denote similar parts in all the views, in which—

Figure 1 is a sectional elevation showing my invention;

55 Fig. 2 is a sectional view on the line 2—2 of Fig. 1;

Fig. 3 is a sectional view on the line 3—3 of Fig. 1;

Fig. 4 is an enlarged sectional view on the line 4—4 of Fig. 1;

Fig. 5 is a sectional view on the line 5—5 of Fig. 4;

Fig. 6 is an enlarged sectional view on the line 6—6 of Fig. 10;

Fig. 7 is an enlarged sectional view on the line 7—7 of Fig. 1;

Fig. 8 is an enlarged sectional view on the line 8—8 of Fig. 7;

Fig. 9 is an enlarged sectional view on the line 9—9 of Fig. 2; and

Fig. 10 is an elevation showing the front of the casing in which the machine is housed.

By referring to the drawings, it will be seen that the body of the machine is housed in a casing 11, and the pump is housed in 75 a casing 12 which is secured to the side of the casing 11.

A pump 13 has a plunger 14 to which is secured a rack 15 at 16 and 17. Pivoted to the top of the rack 15 there is a slotted link 18, to the lower portion of which there is

secured a slotted arm 19, in which a screw 20 is disposed, a nut 21 meshing with this screw and pressing against the slotted arm 19 to hold the arm 19 and the link 18 in 80

position after the angularity of the slotted link 18 is adjusted relatively to the rack 15 and the plunger 14. There is also pivoted to the slotted link 18 at 22 an arm 23 having a scale or prices 24 indicated thereon, 90

the said scale or prices 24 being exhibited through an opening 25 in the rack 15, so that a pointer 26 mounted in the opening 25 in the rack 15 will point to one of the marks indicating a position on the scale, or 95

a stated price. This construction is provided so that the position of the slotted link 18 may be determined relatively to the rack 15 with reference to the market price 100

of the fluid which is to be sold in the vending machine. For instance, if the price of the fluid which is to be sold should be 30 cents a gallon, the bottom of the slotted link would be very much farther away from the bottom of the rack 15 than would be the case 105

if the market price of the fluid to be sold were 10 cents a gallon, for the supply of fluid is shut off when a rack 27 is moved a predetermined distance, the said rack 27 having a roller 28 which is disposed in the 110 slot in the link 18. When the bottom of the link 18 is disposed a considerable dis-

tance from the bottom of the rack 15, the rack 27 will be moved to shut off the supply of fluid much more quickly with a predetermined rate of speed of the pump plunger 14 than would be the case should the bottom of the slotted link 18 be disposed much nearer the bottom of the rack 15.

The rack 27 is disposed in a horizontal position and slides in guideways 29, the teeth of the said rack meshing with the teeth of a gear 30 mounted on a shaft 31. The said shaft 31 leads to a roller clutch 32, shown in Figs. 4 and 5 of the drawings, this clutch 32 being of the usual construction, by means of which the shaft 31 may transmit rotary motion to a shaft 33 when the shaft 31 is rotated in one direction, but which will permit the rotary movement of the shaft 31 in the opposite direction independently of the shaft 33. This construction is provided so that while the pump plunger 14 will transmit motion by the means described to the shaft 33 when the piston plunger 14 moves in one direction, the return movement of the piston plunger may take place without rotating the shaft 33. A friction clutch member 34 is mounted on the shaft 33 and rotates therewith, this friction clutch member 34 being adapted to engage a friction clutch member 35 secured to a shaft 36 which has a gear 37, meshing with a rack 38 secured to the rear of the plate 39. Mounted on the plate 39 there are pins 40, 41, 42, 43, and 44, the pin 44 being disposed adjacent the top of the plate 39, in line with a rack 45; the pin 43 being disposed at a greater distance from the top of the plate 39 and being in line with a rack 46; the pin 42 being disposed a still greater distance from the top of the plate 39 and in line with a rack 47; the pin 41 being disposed approximately an even distance between the top and the bottom of the plate 39 and in line with a rack 48, and the pin 40 being disposed adjacent the bottom of the plate 39 and in line with a rack 49. These pins 40, 41, 42, 43 and 44 are disposed in this manner so that they will serve to cut off the supply of fluid not only with reference to the market price of the fluid, but also with reference to the value of the coin which is introduced in one of the coin slots, there being five coin slots corresponding with the pins 40, 41, 42, 43 and 44 and the racks 45, 46, 47, 48 and 49. A coin slot 50 is used for 5-cent pieces, and the pin 44 on the plate 39, in connection with the means which I will shortly describe, is disposed to cut off the supply of fluid when 5 cents worth of the fluid at the current price has been dispensed, the slotted link 18 having been adjusted with reference to the market price. A coin slot 51 is provided for 10-cent pieces, and the pin 43 is provided to cut off the supply of fluid when 10 cents worth of the fluid

has been dispensed. In a similar manner coin slots 52, 53 and 54 are provided for 25-cent pieces, 50-cent pieces, and silver dollars respectively, the pins 42, 41 and 40 being provided to cut off the supply of fluid when 25 cents worth, 50 cents worth, or a dollar's worth has been dispensed.

Each of the coin slots 50, 51, 52, 53 and 54 is constructed in the same manner, and I will therefore describe only one of the said coin slots, with the mechanism connected therewith. By referring to Fig. 7 of the drawings, it will be seen that the coin chute 54^a leads to a finger 55 disposed below a shoulder 56 on a rod 57, so that when a coin 58 rolls down the coin slot 54 and rests on the finger 55, the coin will be disposed between the finger 55 and the shoulder 56, the bottom of the shoulder 56 and the top of the finger 55 converging slightly away from the coin chute, to hold the coin 58 in this position. An arm 59 is secured to a shaft 60 to which there is also secured a gear wheel 61, there being on this gear wheel 61 a pin 62 which when the gear 61 is rotated engages an arm 63 secured to a shaft 64, to which the finger 55 is also secured so that when the shaft 60 is rotated it will rotate the gear 61, and with it the pin 62, and the pin 62 will engage the arm 63 to rotate the shaft 64, thereby raising the finger 55, which presses the coin 58 against the rod 57 upwardly sufficiently far to bring the rack teeth 65 on the rod 57 into mesh with the gear teeth on the gear 61. It will be understood that when the arm 59 is rotated further the rod 57 will be raised by means of the engagement of the teeth on the gear 61 with the rack teeth 65.

The shaft 60 extends across the machine, and there are five gears 61 mounted on the said shaft, and there are five sets of fingers 55 and arms 63, one of the fingers 55 being disposed adjacent the bottom of each of the coin chutes 54^a. The five rods having shoulders 56, are shown in Fig. 1 of the drawings as numbered 57, 57^a, 57^b, 57^c, and 57^d. When one of these rods 57, 57^a, 57^b, 57^c, or 57^d is raised, it pushes against one of the cams 66 on a shaft 67, to rotate the said shaft 67, this shaft 67 having a crank 68, to which is articulated a link 69. This link 69 is connected with a valve 70 at 71. There is also secured to this link 69 at 72 an arm 73 of a lever 74 which is pivoted at 75, and which has rollers 76 disposed in an annular groove in a part of the clutch member 34 to operate the said clutch member. It will, therefore, be seen that when the coin is introduced in one of the slots, and the arm 59 is rotated to rotate the shaft 60, the rod 57 will press up on one of the cams 66 to rotate the shaft 67, by which means the valve 70 will be opened to an outlet, and the clutch member 34 will be pressed into engagement with the

clutch member 35. This will not only open the outlet so that the fluid may be dispensed when the pump is operated by means of a handle 77, in a manner readily understood, 5 but it will also by the engagement of the clutch member 34 with the clutch member 35 cut off the supply of fluid when the proper amount has been dispensed with reference to the value of the coin which has 10 been introduced in the coin slot in the machine, for with the rotation of the clutch member 35 and the shaft 36, the plate 39 will be raised in the manner which has been described, and one of the pins 40, 41, 42, 43, 15 44 on the plate 39 will engage a trigger which I will now describe, to shut off the flow of the fluid.

There is secured to the rear of each of the rods 57 a trigger 78, the bottom of which 20 is shown clearly in Fig. 9 of the drawings, the bottom of each trigger 78 being disposed through an opening 79 is a support 80, and there being springs 81 at the side of each opening 79 for moving the trigger 78 laterally when it is raised, so that it will rest on the support 80 at its shoulder 82, and remain in this position until one of the pins 40, 41, 42, 43, 44 engages a cam surface 83 at its bottom to push the trigger 78 back to a position where it may move downwardly in its opening 79 to normal position.

When the rod 57 is raised by means of the gear wheel 61, the trigger 78 will be supported by its engagement at its shoulder 82 35 with the support 80, and it will remain in this position until its lower end is pushed back into a position where it may again slide downwardly in its slot 79 in the support 80. This will again rotate the shaft 40 67 to operate the link 69 to move the clutch member 34 away from the clutch member 35, and to close the outlet of the valve 70. If desired, a spring may be mounted on the shaft 67 to assist in this return movement. 45 When the clutch member 34 has been moved away from the clutch member 35, the plate 39 will move downwardly in its guides 84.

As a means to prevent a person from holding one of the rods 57 up after it has been 50 raised by means of the arm 59, I prefer to cut the shaft 60 and separate the parts by a clutch 85, so that by means of a lever 86 I can move one part of the clutch 85 away from its companion part, and thereby cut 55 off communication between the arm 59 and the gear 61. Secured to the plate 39 there is a cam rod 87 which engages the lever 86 to move one part of the clutch 85 away from its companion part as soon as the plate 39 moves 60 upwardly a short distance.

The rack 15 meshes with a gear wheel 88 mounted on a shaft 89 which is connected with a roller clutch 90 similar to that shown in Figs. 4 and 5 of the drawings, by means 65 of which the shaft 89 is adapted to rotate a

clutch member 91 in one direction, but is prevented from rotating the said clutch member in the opposite direction. With this roller clutch 90 and clutch member 91, is adapted to be engaged a companion clutch 70 member 92 as a means for rotating a dial 101, this dial 101 being provided to indicate the amount of fluid which has been dispensed and the amount of fluid still contained in the tank. The clutch member 92 75 slides up and down out of and into engagement with the clutch member 91, and it is operated in a manner readily understood, by means of a lever 93 fulcrumed at 94, and to which a link 95 is articulated, this link 95 80 being articulated to an arm 96 secured to the shaft 67. When one of the rods 57 is raised to rock the shaft 67 by means of a cam 66, the shaft 67 not only serves to move the rod 69 to throw the clutch member 34 85 into engagement with the clutch member 35 and to open the outlet of the valve 70, but it also serves by means of the arm 96, the link 95 and the lever 93, to move the clutch member 92 down into engagement with the 90 clutch member 91. The clutch member 92 rotates with a shaft to which a gear 97 is secured, this gear 97 meshing with the teeth 98 on the dial plate 101, the dial plate 101 having numbers or characters 99 thereon 95 which show one at a time through an opening 100 in the casing 11, to indicate the amount of fluid which has been dispensed, as the dial 101 will rotate with each operation of the pump.

Secured to the rear of the dial 101 there is a ratchet wheel 102 which is engaged by a pawl 103 on a lever 104 fulcrumed at 105, a second lever 106 being articulated to the end 107 of the lever 104. The lever 104 is 105 held yieldingly in position by means of a spring 108 and the lower end of the lever 106 is held yieldingly against a stop 109 by means of a spring 110 which connects the upper portion of the lever 106 with the lever 110 104. The lever 106 has a shoulder 111 which, when the lever 104 is moved by the movement of the pawl 103 over one of the ratchet teeth, will pass below a spring contact member 112, so that the return movement of the lever 104 will raise the lever 106, and the shoulder 111 thereon will engage the end of the spring contact member 112 to move the said spring contact member into engagement with a companion contact member 113. This will momentarily close the circuit 114 having a battery 115, there being a solenoid 116 in this circuit at any desired distance. When the solenoid 116 is energized by the closing of the circuit, it will act 115 on an armature 117 and move a lever 118 so that a pawl 119 mounted thereon, and which engages the teeth of a ratchet wheel 120, will act on the said teeth to move the ratchet wheel 120 a step corresponding with the 120 125

movement of the ratchet wheel 102. The lever 118 is held yieldingly in position by means of a spring 121, and the pawl 119 is held yieldingly in position on the lever 118 by means of a spring 122. Secured for rotating with the ratchet wheel 120 there is a dial 123 which corresponds with the dial 101, the purpose of this arrangement being to enable the proprietor at a distance 10 from the machine to keep track of the quantity of fluid dispensed by the machine and the quantity of fluid still remaining in the machine.

Each of the coin chutes 54^a has an opening 124 therein, a movable section 125 being pivoted at 126 for closing this opening. A spring 127 is provided for holding the section 125 in normal position, as indicated in Figs. 7 and 8 of the drawings, there being 20 disposed below the section 125 a magnet 128 which when an iron slug is rolled into the chute 54^a, will serve to upset the section 125, inasmuch as the magnet 128 will draw the iron slug downwardly, and as the lower 25 edge of the iron slug will press against the edge 129 of the coin chute section 125, it will cause the section 125 to rotate. The rotary movement of the section 125, together with the upturned edge 129 of the section, 30 will throw the iron slug clear of the magnet 128, so that it will be out of the way.

As a means of closing the coin chutes when all the fluid has been dispensed, I provide the dial 101 with a projection 130, 35 which when the dial 101 rotates to a predetermined position, will engage a crank arm 131 on a rock shaft 132 journaled in bearings 133, this rock shaft 132 having another crank arm 134 which will press a trigger 135 against the resiliency of a spring 138, so that a shoulder 136 on the trigger 135 will be moved clear of a stop 137 and a shutter 139 will be moved downwardly under the influence of springs 140, this shutter 139 45 moving to a position at the rear of the coin slots to close the latter.

The coin from the finger 55 passes to a vertical coin chute 141, and then to a coin chute 142, the end 143 of which is turned up 50 to hold a predetermined number of coins on the chute 142, the coin at the end 143 of the chute being pushed off when a coin rolls against the said predetermined number of coins on the chute 142. There is a glass 55 window in the frame 11, through which the said coins on the chute 142 may be examined.

Having thus described my invention, I claim as new and desire to secure by Letters Patent:

60 1. In a fluid vending machine, a slotted link, means to adjust the angularity of the link relatively to its path of movement, a member disposed for moving at an angle to the link and having a projection in the slot 65 in the link, a valve, means for operating the

valve, and means to actuate the second mentioned means adapted to be operated by the member.

2. In a fluid vending machine, a pump plunger, a slotted link, means on the pump 70 plunger for supporting the slotted link and which permits of the adjustment of the angularity of the slotted link relatively to the direction of movement of the pump plunger, a member disposed for moving at 75 an angle to the link and having a projection in the slot, a valve, means for operating the valve, and means to actuate the second mentioned means adapted to be operated by the member.

3. In a fluid vending machine, a pump plunger, a slotted link, means on the pump plunger for supporting the slotted link and which permits of the adjustment of the angularity of the link relatively to the direction of movement of the pump plunger, a rack 85 for moving transversely of the path of movement of the pump plunger and having a projection disposed in the slot in the link, a pinion meshing with the rack teeth, a 90 valve, means for operating a valve, and means to actuate the second mentioned means adapted to be operated by the member.

4. In a fluid vending machine, a pump 95 plunger, a slotted link pivotally connected with the pump plunger, an arm mounted on the slotted link and having a scale which may be read relatively to the markings on the pump plunger for determining the angularity of the slotted link relatively to the pump plunger, means for securing the slotted link in adjusted position relatively to the pump plunger, a member disposed for moving at an angle to the link and having 100 a projection in the slot, a valve, means for operating the valve, and means to operate the second mentioned means adapted to be actuated by the member.

5. In a fluid vending machine, a pump 110 having a plunger, a valve connected with the pump, means to operate the valve, means to move the first means to one position, means to free the second mentioned means to permit the first mentioned means to move 115 to another position, a slotted link, means on the pump plunger for supporting the slotted link and which permits of the adjustment of the angularity of the slotted link relatively to the direction of movement of the 120 pump plunger, and means by which the pump is adapted to operate the third mentioned means.

6. In a fluid vending machine, a pump, a valve connected therewith, means to operate 125 the valve, means to operate the first mentioned means to move the valve to a predetermined position, a third means to free the first mentioned means to permit the valve to move to another position, and means oper- 130

able by the pump for operating the third mentioned means.

7. In a fluid vending machine, a pump, a valve connected therewith, means to operate the valve, a second means to operate the first mentioned means to move the valve to a predetermined position, a third means to free the first mentioned means to permit the valve to move to another position, a slotted link movably connected with the pump, means on the pump for supporting the slotted link and which permits of the adjustment of the angularity of the link with reference to the direction of movement of the pump, a member disposed in the slot in the link, and means operable by the member for actuating the third mentioned means.

8. In a fluid vending machine, a pump having a plunger, a valve connected with the pump, means to operate the valve, means to operate the first means, another means to free the first means, and means operable by the pump for moving the third means when the pump plunger moves in one direction but which does not act on the third means when the pump plunger moves in the opposite direction.

9. In a fluid vending machine, a pump having a plunger, a valve connected with the pump, means to operate the valve, means to operate the first mentioned means, another means for freeing the first mentioned means, a slotted link, means on the pump plunger for supporting the slotted link and which permits of the adjustment of the angularity of the link relatively to the direction of movement of the pump plunger, and means having a member disposed in the slot in the link for operating the third mentioned means.

10. In a fluid vending machine, a pump having a plunger, a valve connected with the pump, means to operate the valve, means to operate the first mentioned means, another means for freeing the first mentioned means, a clutch member communicating with the third mentioned means, a companion clutch member, means by which the pump plunger is adapted to operate the companion clutch member, and means operable by the first mentioned means for moving the second mentioned clutch member into and out of engagement with the first mentioned clutch member.

11. In a fluid vending machine, a pump having a plunger, a valve connected with the pump, means to operate the valve, means to operate the first mentioned means, a third means for freeing the first mentioned means, a clutch member connected with the third mentioned means, a companion clutch member, means by which a movement of the pump plunger in one direction is adapted to rotate the companion clutch member but which will not operate the latter when the

pump plunger moves in the opposite direction, and means operable by the first mentioned means for moving the second clutch member into and out of engagement with the first clutch member.

12. In a fluid vending machine, a pump having a plunger, a valve connected with the pump, means to operate the valve, means to operate the first mentioned means, a third means for freeing the first mentioned means, a clutch member connected with the third mentioned means, a companion clutch member, a slotted link, means on the pump plunger for supporting the slotted link and which permits of the adjustment of the angularity of the link relatively to the direction of movement of the pump plunger, a member disposed in the slot in the link, means by which the last mentioned member is adapted to operate the companion clutch member, and means operable by the first mentioned means for moving the second mentioned clutch member into and out of engagement with the first mentioned clutch member.

13. In a fluid vending machine, a pump, a valve connected with the pump, means to operate the valve, means to hold the first mentioned means when moved to a predetermined position, means to free the first mentioned means from the second mentioned means, a clutch member communicating with the third mentioned means, a companion clutch member, means by which the pump is adapted to operate the companion clutch member, and means operable by the first mentioned means for moving the second clutch member into engagement with the first clutch member.

14. In a fluid vending machine, a pump having a plunger, a valve connected with the pump, means to operate the valve, means to hold the first mentioned means when moved to a predetermined position, means to free the first mentioned means from the second mentioned means, a clutch member communicating with the third mentioned means, a companion clutch member, a slotted link, means on the pump plunger for supporting the slotted link and which permits of the adjustment of the angularity of the link relatively to the direction of movement of the pump plunger, a member disposed in the slot in the link, means by which the last mentioned member is adapted to operate the companion clutch member, and means operable by the first mentioned means for moving the second mentioned clutch member into engagement with the first mentioned clutch member.

15. In a fluid vending machine, a pump, a valve connected with the pump, means to operate the valve, means to operate the first mentioned means, a third means to free the first mentioned means which is adapted to

throw the second mentioned means out of operative position, and means by which the pump is adapted to operate the third mentioned means.

- 5 16. In a fluid vending machine, a pump, a valve connected therewith, a shaft having a crank, a link connecting the crank with the valve for operating the latter, a cam on the shaft, a rod having a shoulder and rack 70 teeth, for engaging the cam to rock the shaft, a trigger carried by the rod and having a shoulder, a support on which the trigger at its shoulder is adapted to rest when the rod is operated, a pivoted finger between 75 which and the shoulder on the rod a coin is adapted to be disposed, an arm secured to the finger, a gear with its teeth out of mesh with the rack teeth when the machine is not in use, a pin on the gear disposed for engaging 80 the arm when the gear is rotated by which means the finger will be raised to press the coin against the shoulder to move the rack teeth into mesh with the gear teeth so that a further movement of the gear will 85 raise the rod without the assistance of the coin, and means by which the pump is adapted to free the trigger at its shoulder from the support when it has discharged a predetermined quantity of the fluid. 90
- 30 17. In a fluid vending machine, a pump, a valve connected therewith, a rod having a shoulder and rack teeth, means by which the rod is adapted to operate the valve, a trigger carried by the rod and having a 95 shoulder, a support on which the trigger at its shoulder is adapted to rest when the rod is operated, a pivoted finger between which and the shoulder on the rod a coin is adapted to be disposed, an arm secured to the 100 finger, a gear with its teeth out of mesh with the rack teeth when the machine is not in use, a pin on the gear disposed for engaging the arm when the gear is rotated by which means the finger will be raised to 105 press the coin against the shoulder to move the rack teeth into mesh with the gear so that a further rotation of the gear will move the rod without the assistance of the coin. 110
- 35 18. In a fluid vending machine, a pump, a valve connected therewith, a rod having a shoulder and rack teeth, means by which the rod is adapted to operate the valve, a trigger carried by the rod and having a shoulder, a support on which the trigger at its shoulder is adapted to rest when the rod is operated, a pivoted finger between which and the shoulder on the rod a coin is adapted to be disposed, an arm secured to the 115 finger, a gear with its teeth out of mesh with the rack teeth when the machine is not in use, a pin on the gear disposed for engaging the arm when the gear is rotated by which means the finger will be raised to 120 press the coin against the shoulder to move the rack teeth into mesh with the gear so that a further rotation of the gear will move the rod without the assistance of the coin. 125
- 40 19. In a fluid vending machine, a pump, a valve, a rod having a shoulder and rack teeth, means by which the rod is adapted to operate the valve, a pivoted finger between which and the shoulder a coin is adapted to be disposed, an arm secured to the finger, a gear with its teeth out of mesh with the rack teeth when the machine is not in use, and a pin on the gear disposed for engaging the arm when the gear is rotated by which means the finger will be moved to press the coin against the shoulder to move the rack teeth into mesh with the gear so that a further rotation of the gear will move the rod without the assistance of the coin. 130
- 45 20. In a fluid vending machine, a pump, a valve, a rod having a shoulder and rack teeth, means by which the rod is adapted to operate the valve, a pivoted finger between which and the shoulder a coin is adapted to be disposed, a gear with its teeth out of mesh with the rack teeth when the machine is not in use, and means by which the gear is adapted to move the finger to press the coin against the shoulder to move the rack teeth into mesh with the gear so that a further rotation of the gear will move the rod without 135 the assistance of the coin. 140
- 50 21. In a fluid vending machine, a pump, a valve, a rod having a shoulder and rack teeth, means by which the rod is adapted to operate the valve, a pivoted finger between which and the shoulder a coin is adapted to be disposed, an arm secured to the finger, a gear with its teeth out of mesh with the rack teeth when the machine is not in use, a pin on the gear disposed for engaging the arm when the gear is rotated by which means the finger will be moved to press the coin against the shoulder to move the rack teeth into mesh with the gear so that a further rotation of the gear will move the rod without 145 the assistance of the coin, and resilient means to hold the arm yieldingly in operative position. 150
- 55 22. In a fluid vending machine, a pump, a valve connected therewith, a clutch member, means by which the pump is adapted to drive the clutch member, a companion clutch member, a rod having means for operating the first clutch member and the valve, means for operating the rod, means 155

gaging the arm when the gear is rotated by which means the finger will be raised to press the coin against the shoulder to move the rack teeth into mesh with the gear teeth so that a further movement of the gear will raise the rod without the assistance of the coin, means to free the trigger at its shoulder from the support, and means by which the movement of the pump in one direction will operate the second mentioned means 75 while the pump is free to move in the other direction independently of the second mentioned means.

19. In a fluid vending machine, a pump, a valve, a rod having a shoulder and rack 80 teeth, means by which the rod is adapted to operate the valve, a pivoted finger between which and the shoulder a coin is adapted to be disposed, an arm secured to the finger, a gear with its teeth out of mesh with the rack 85 teeth when the machine is not in use, and a pin on the gear disposed for engaging the arm when the gear is rotated by which means the finger will be moved to press the coin against the shoulder to move the rack teeth into mesh with the gear so that a further rotation of the gear will move the rod without the assistance of the coin. 90

20. In a fluid vending machine, a pump, a valve, a rod having a shoulder and rack 95 teeth, means by which the rod is adapted to operate the valve, a pivoted finger between which and the shoulder a coin is adapted to be disposed, a gear with its teeth out of mesh with the rack teeth when the machine is not 100 in use, and means by which the gear is adapted to move the finger to press the coin against the shoulder to move the rack teeth into mesh with the gear so that a further rotation of the gear will move the rod without 105 the assistance of the coin. 110

21. In a fluid vending machine, a pump, a valve, a rod having a shoulder and rack teeth, means by which the rod is adapted to operate the valve, a pivoted finger between 115 which and the shoulder a coin is adapted to be disposed, an arm secured to the finger, a gear with its teeth out of mesh with the rack teeth when the machine is not in use, a pin on the gear disposed for engaging the arm when the gear is rotated by which means the finger will be moved to press the coin against the shoulder to move the rack teeth into mesh with the gear so that a further rotation of the gear will move the rod without 120 the assistance of the coin, and resilient means to hold the arm yieldingly in operative position. 125

22. In a fluid vending machine, a pump, a valve connected therewith, a clutch member, means by which the pump is adapted to drive the clutch member, a companion clutch member, a rod having means for operating the first clutch member and the valve, means for operating the rod, means 130

for operating the third mentioned means, and means adapted to be actuated by the companion clutch member for freeing the third mentioned means from the fourth mentioned means.

23. In a fluid vending machine, a pump, a valve connected therewith, means for operating the valve, means for operating the first mentioned means, and means operable by the pump for disconnecting the second mentioned means from the first mentioned means.

24. In a fluid vending machine, a pump, a valve connected therewith, a rod having rack teeth, means by which the rod is adapted to operate the valve, a gear, means for moving the rack teeth into mesh with the gear, means for rotating the gear, means for holding the rod in operative position, and means operable by the pump for disconnecting the third mentioned means and for freeing the rod from the fourth mentioned means.

25. In a fluid vending machine, a pump, a valve connected therewith, a rod having rack teeth, means by which the rod is adapted to operate the valve, a gear, means for moving the rack teeth into mesh with the gear, means for rotating the gear, a clutch member for operating the third mentioned means, a companion clutch member, means for operating the companion clutch member, means for holding the rod in operative position, and means operable by the pump for moving one clutch member relatively to the other clutch member and for freeing the rod from the fifth mentioned means.

26. In a fluid vending machine, a pump, a valve connected therewith, a plurality of rods each having rack teeth, means by which each rod is adapted to operate the valve, a plurality of gears one for each rod, means for moving the rack teeth into mesh with the gears, means for rotating the gears so that the rod having the rack teeth which have been moved into mesh with the gear will be advanced by the rotation of the gear, means for holding the rod so advanced in operative position, a plate, pins on the plate one for each rod, means in connection with the pins for freeing the rod held by the fourth mentioned means, the pins being disposed each a different distance from the fifth mentioned means than the other pins, and means by which the pump is adapted to move the plate in the direction of the fifth mentioned means.

27. In a fluid vending machine, a pump, a valve connected therewith, a plurality of rods each having rack teeth, means by which each rod is adapted to operate the valve, a plurality of gears one for each rod, means for moving the rack teeth into mesh with the gears, means for rotating the gears so that the rod having the rack teeth which

have been moved into mesh with the gear will be advanced by the rotation of the gear, means for holding the rod so advanced in operative position, a plate, pins on the plate one for each rod, means in connection with the pin for freeing the rod held by the fourth mentioned means, the pins being disposed each a different distance from the fifth mentioned means than the other pins, and means by which a movement of the pump in one direction will move the plate in the direction of the fifth means, while the pump is free to move in the opposite direction independently of the plate.

28. In a fluid vending machine, a pump, a valve connected therewith, a plurality of rods each having rack teeth, means by which each rod is adapted to operate the valve, a plurality of gears one for each rod, means for moving the rack teeth into mesh with the gears, means for rotating the gears so that the rod having the rack teeth which have been moved into mesh with the gear will be advanced by the rotation of the gear, means for holding the rod so advanced in operative position, a plate, pins on the plate one for each rod, means in connection with the pins for freeing the rod held by the fourth mentioned means, the pins being disposed each a different distance from the fifth mentioned means than the other pins, means by which the pump is adapted to move the plate in the direction of the fifth mentioned means, and means operable by the plate for disconnecting the third mentioned means.

29. In a fluid vending machine, a member, means to adjust the angularity of the member relatively to its path of movement, a second member for moving at an angle to the path of movement of the first mentioned member and having a projection disposed against the first member to be operated thereby, a valve, means for operating the valve, and means to move the second member into inoperative position adapted to be actuated by the second mentioned means.

30. In a fluid vending machine, a pump, a valve connected therewith, a dial for indicating quantities of a fluid discharged by the pump, driving means operated by the pump, means for operating the dial and adapted to be driven by the driving means, and means for simultaneously operating the valve and for throwing the second mentioned means into operative position.

31. In a fluid vending machine, a pump, a valve connected therewith, a dial for indicating quantities of a fluid discharged by the pump, driving means operated by the pump, means for operating the dial and adapted to be driven by the driving means, means for operating the valve and for throwing the second mentioned means into

operative position, and means by which the pump after a predetermined period of operation is adapted to actuate the third mentioned means.

- 5 32. In a fluid vending machine, a pump, a valve connected therewith, a dial for indicating quantities of fluid discharged by the pump, driving means operated by the pump, means for operating the dial and adapted
10 to be driven by the driving means, means for operating the valve and for throwing the second mentioned means into operative position, a clutch member, means by which the pump is adapted to operate the clutch
15 member, a companion clutch member, means

by which the companion clutch member is adapted to operate the third mentioned means, and means by which the third mentioned means is adapted to operate one of the clutch members. 20

33. In a fluid vending machine, a coin chute, a dial having a projection, a slide for closing the coin chute, a trigger secured to the slide and having a shoulder, a stop on which the trigger at its shoulder normally 25 rests, a rock shaft having an arm disposed for engagement by the projection on the dial, and another arm engaging the trigger to remove the shoulder from the stop.

JASON McGREGOR CHANDLER.
